11 WALTER L. ROTHSCHILD

UNITED STATES PATENT OFFICE.

WALTER L. ROTHSCHILD, OF NEW ROCHELLE, NEW YORK.

DISPLAY BOX.

Application filed September 23, 1925. Serial No. 58,039.

The object of my invention is to provide a display box which will have three advantages, namely, (1) the box may be readily erected to its display condition without spilling the contents, (2) the box may be closed and packed without any projecting part, and (3) the contents of the box will be held firmly in place while being displayed. This and other objects are accomplished by my invention, one embodiment of which is more particularly set forth.

For a more detailed description of my invention, reference is to be had to the accompanying drawings, forming a part hereof, in which

Figure 1 is a sectional view of my improved box when erected.

Figure 2 is a front elevation of the same.

Figure 3 is a sectional view, taken on the line 3—3 of Figure 1, looking in the direction of the arrows.

Figure 4 is a sectional view showing the cover while about to be lowered on the box.

Figure 5 is a perspective view of the inside of the cover.

Throughout the various views of the drawings, similar reference characters designate similar parts.

My improved box 1 has a cover 2 which contains a stand 3 which is secured to its interior and composed of three parts, namely, a base 4, a short flap 5 and a long flap 6. The short flap has a tongue 7 which is adapted to enter a slot 8 in the long flap 6 so that when this tongue 6 enters at the top of this slot and is shoved down, the stand 3 is held erect, as shown in Figures 1 and 3. By reversing this operation the stand may be disassembled and it will then lie flat in the cover 2, or substantially so.

The cover 2 may be made in any suitable way and for ordinary cardboard boxes it is preferably made, as shown, that is with a top 9 and laterally extending flanges 10 which are secured together and to the top, in the conventional manner.

The box 1 has a bottom 11 which is a little smaller than the top 9 and corresponding flanges or sides 12, of the conventional kind, so that a description is unnecessary.

If desired, it may also have a number of partitions 13 which divide the box into compartments and it may also have a flat portion 14 on which any display device may be placed. In the preferred embodiment of my invention horizontal strips 15 are also provided at the bottom of each compartment and in front of the same so as to have a projecting edge, as indicated in Figure 4, which edge will prevent the contents of the box 60 from falling out.

In view of the foregoing, the erection and packing of my improved box will be readily understood. It is packed in the conventional manner by putting the cover in place with the flaps, as shown in Figures 4 and 5, and then it looks like an ordinary box and may be shipped and stored as such. When it is to be erected, the cover is first removed and the box allowed to lie flat and after the cover 70 is removed the stand 3 is erected, as above described, and then the bottom is placed in the cover, as shown in Figure 1, so that it is possible for the person erecting the display box to do so without any danger of dumping out the contents. To prevent the contents from falling out too easily, the strips 15 function as above described.

While I have shown and described my improved display box as suitable for buttons 80 mounted on cards, it is obvious that it is not restricted thereto, but that it may be used whenever desirable, and this invention covers all boxes that come within the scope 85 of the annexed claim.

Having thus described my invention, what I claim is:

A display box having a cover with a stand secured therein, the stand being composed of a central part secured to the cover and two flaps, one of which is adapted to engage the other and a box with compartments, means adjacent to the compartments for preventing the contents from falling out and means near the compartments for a display 95 device.

In testimony whereof, I have hereunto set my hand this 3rd day of September, 1925.

WALTER L. ROTHSCHILD.
